United States Patent

Des. 235,884
Patented July 15, 1975

235,884

POCKET LIGHTER

Franz Alban Stuetzer, Mühlheim am Main, Germany,
assignor to Rowenta-Werke, G.m.b.H.

Filed July 26, 1974, Ser. No. 492,139

Claims priority, application Germany, Jan. 31, 1974

Term of patent 14 years

Int. Cl. D27—05

U.S. Cl. D27—42

FIG. 1 is a perspective view of a pocket lighter showing my new design including the top, front, and one side thereof;

FIG. 2 is a side elevational view showing the side opposite to that shown in FIG. 1;

FIG. 3 is a rear elevational view thereof;

FIG. 4 is a top plan view thereof; and

FIG. 5 is a bottom plan view thereof.

I claim:

The ornamental design for a pocket lighter, as shown and described.
